METHOD AND APPARATUS FOR LIQUEFYING
GASEOUS FLUIDS

Lilburn C. Claitor and Duffer B. Crawford, Jeanette, Pa., assignors to Elliott Company, Jeanette, Pa., a corporation of Pennsylvania

Application October 4, 1948, Serial No. 52,678

12 Claims. (Cl. 62—123)

1

This invention relates to a method and apparatus for liquefying a low volatile gaseous fluid, and is particularly advantageous for producing liquid air.

Most of the well-known processes for producing liquid air do not provide satisfactory means for removing condensable impurities, such as water vapor, carbon dioxide, and volatile hydrocarbons that are present in the atmosphere in varying concentrations. In order to prevent these impurities from fouling the liquefaction apparatus, in one type of liquid air plant the entering air is chemically cleaned, which involves considerable expense and inconvenience. In more modern liquid air plants, the air is usually introduced into the liquefying apparatus under high pressure and is there cooled and partially liquefied by indirect heat exchange with cold air at substantially atmospheric pressure in reversible heat exchangers or regenerators. The air passages in the latter apparatus must operate alternately on high and low pressure gas streams, and the periodic opening and closing of the valves when the gas streams are switched from one heat exchange unit to the other, causes pressure shocks in the system that upset its balanced operation. In addition, heat exchangers and regenerators, when used under these circumstances, seldom remove all of the condensable impurities from the entering air, because the temperatures attained therein are not sufficiently low. The air being under considerable pressure is liquefied at a temperature substantially above its normal boiling point at atmospheric pressure, so that some of the carbon dioxide and volatile hydrocarbons will not be condensed in the exchangers where they could be easily removed. These residual impurities, however, will be deposited further along in the system where the temperature of the liquid air is lowered by throttling to substantially atmospheric pressure. In such cases, these impurities may plug piping, valves, etc., and can be removed only by shutting down the plant and interrupting its otherwise continuous operation. In other words, while there are recognized advantages in liquefying air under pressure, there are disadvantages to purifying it under pressure, which so far as we are aware have not heretofore been eliminated in a liquid air plant. The same is true in the liquefaction of other gaseous fluids.

It is accordingly among the objects of this invention to provide a method and apparatus for liquefying gaseous fluids, including gaseous mixture such as air, in which substantially all of the condensable impurities in the entering gaseous

2

fluid will be simply and economically removed before the gaseous fluid is liquefied so that the impurities may be purged from the system without interrupting its continuous operation, and in

- 5 which there are no appreciable pressure shocks to the system when switching from one heat exchanging unit to another so that continuous operation in a state of equilibrium can be attained.
- 10 In accordance with this invention, the gaseous fluid to be liquefied, such as air, is admitted to the system and purified at substantially atmospheric pressure, but is liquefied at a higher pressure. In both the purification (low pressure) and liquefaction (high pressure) cycles the gaseous fluid is cooled by cold purified fluid at substantially atmospheric pressure. Low pressure gaseous fluid entering the system is cooled in one of two reversible heat exchangers by indirect
- 15 heat exchange with a first portion of cold purified gaseous fluid that is at about its liquefaction temperature and at substantially atmospheric pressure. In this way, the entering gaseous fluid can be cooled to within a few degrees of its liquefaction temperature, so that substantially all of its condensable low volatile impurities (i. e. those having a higher boiling point than the fluid to be liquefied) will be condensed and deposited on the heat exchanger surfaces, from which they
- 20 can be removed in the usual manner after switching the gas streams over to the other exchanger. The entering gaseous fluid that has been so cooled and purified is then further cooled to about its liquefaction temperature by heat exchange with
- 25 cold fluid, consisting of purified gaseous fluid in either the liquid or vapor state. As previously stated, gas fluid that has been previously purified and cooled to its liquefaction temperature is used to cool the entering gas fluid and is thereby
- 30 removed in the usual manner after switching the gas streams over to the other exchanger. The entering gaseous fluid that has been so cooled and purified is then further cooled to about its liquefaction temperature by heat exchange with
- 35 cold fluid, consisting of purified gaseous fluid in either the liquid or vapor state. As previously stated, gas fluid that has been previously purified and cooled to its liquefaction temperature is used to cool the entering gas fluid and is thereby
- 40 removed in the usual manner after switching the gas streams over to the other exchanger. The entering gaseous fluid that has been so cooled and purified is then further cooled to about its liquefaction temperature by heat exchange with
- 45 cold fluid, consisting of purified gaseous fluid in either the liquid or vapor state. As previously stated, gas fluid that has been previously purified and cooled to its liquefaction temperature is used to cool the entering gas fluid and is thereby
- 50 removed in the usual manner after switching the gas streams over to the other exchanger. The entering gaseous fluid that has been so cooled and purified is then further cooled to about its liquefaction temperature by heat exchange with
- 55 cold fluid, consisting of purified gaseous fluid at substantially atmospheric pressure. The liquefied gaseous fluid is collected in a receiver. The remainder of the compressed gaseous fluid is expanded to substantially atmospheric pressure with the performance of external work, so

as to cool it further to about its liquefaction temperature. This latter portion augments the supply of cold purified gaseous fluid in the system. The second portion of cold purified gaseous fluid (the cooling agent in the liquefaction cycle) is compressed and recycled as additional feed after it has absorbed as much heat as possible from the compressed gaseous fluid, as previously described.

The preferred embodiment of this invention, which is herein described with reference to the liquefaction of air but is equally applicable to other gaseous fluids, is diagrammatically illustrated in Fig. 1 of the accompanying drawings. Figs. 2, 3, and 4 show modifications of a part of Fig. 1.

Referring to Fig. 1, air is forced into the system by a blower 1 at a pressure not materially exceeding that required to overcome the frictional resistance to its travel. Usually a pressure at the blower of less than 20 lbs. per square inch absolute, which is referred to herein as being substantially atmospheric pressure, is sufficient to assure movement of the air through the purifying apparatus. Such a pressure is easily obtainable in various types of blowers that require no internal lubrication and accordingly do not contaminate the air with undesirable hydrocarbons. The heat of compression is removed from the air by an after-cooler 2 of conventional type. A large proportion of the moisture contained in the air is condensed in a dehumidifier 3, which may be either a refrigeration unit, a silica-gel dryer, or other conventional apparatus for accomplishing this purpose. The partially dehumidified air is then led to one of a pair of heat exchangers 4 or 5, as determined by the operation of appropriate valves. It will be assumed herein that the air is flowing for the time being through exchanger 4, where it is cooled to about -305° F. by indirect heat exchange with approximately the same number of mols of cold purified air at about its liquefaction temperature (around -314° F.) and at substantially atmospheric pressure flowing in a countercurrent direction through the same exchanger.

Heat exchangers 4 and 5 are of the usual type providing indirect heat exchange between countercurrent flows of two gases. They are preferably connected and operated as described in the co-pending application of Duffer B. Crawford, one of the applicants herein, for a Gas purification method and apparatus, Serial No. 662,937, filed April 18, 1946, and are so shown in the attached drawing. When so connected and operated, these heat exchangers may be continuously and economically used for indefinitely long periods. When impurities condensed from the entering air in one exchanger begin to impair its performance appreciably, the cold purified air and the incoming air are switched over to the other exchanger. The impurities condensed in the first exchanger are then removed by passing some of the warm purified air leaving the second exchanger through the cold purified air passage of the first exchanger in a reverse direction to its usual flow, i. e. from the warm to the cold end of the exchanger, and then through the incoming air passage of the same exchanger in a reverse direction to the usual flow of incoming air, i. e. from the cold to the warm end of the exchanger. In this clean-up cycle, the condensed impurities in the incoming air passage are sublimed and carried out of the exchanger by the warm purified air passed therethrough and, along with this air,

are discharged into the atmosphere. In this clean-up operation, only a minimum amount of heat is transferred to the first exchanger, resulting in economy of refrigeration. Further description of exchangers 4 and 5 and the manner of operating them will be found in the copending application referred to and need not be repeated here.

The incoming air purified in exchanger 4 leaves 10 that exchanger at a temperature of about -305° F. and is led by a pipe 6 preferably to an accumulator, or cold reservoir, 7 that is filled with silica gel, activated charcoal, alumina, or other suitable material. Because of the heat capacity of such a substance, it acts as a reservoir of refrigeration and, because of its absorbent capacity for air at very low temperatures, as a reservoir of air. These characteristics of the accumulator 20 decrease the small temperature and pressure fluctuations in the air stream caused by switching the incoming air from one of the heat exchangers, 4 or 5, to the other at the beginning of each clean-up cycle.

From the accumulator, the air is led by a pipe 25 8 to coil 9 immersed in liquid air in a liquid air receiver 10. In flowing through this coil, the air is further cooled to about -314° F., which is about its liquefaction temperature. This cold purified air is then led back by a pipe 11 to the 30 cold purified air passage in exchanger 4, where it cools the incoming air as previously described and is itself warmed to about the temperature of the incoming air entering that exchanger. A portion of this warmed pure air is used to defrost, 35 or clean-up, the impurities previously condensed in exchanger 5 and along with those impurities is then discharged into the atmosphere through pipe 12. The remainder of the warmed pure air leaving exchanger 4 passes through pipe 13 to 40 the liquefaction cycle of the system.

It is a feature of this invention that the entering air is at low pressure and is cooled in a heat exchanger by cold purified air likewise at low pressure and at about its liquefaction temperature, so that the temperature at the cold end of the exchanger is sufficiently low to cause substantially all of the low volatile condensable impurities contained in the entering air, such as carbon dioxide and acetylene, to be deposited on the heat exchanger surfaces, from which they can be removed (after switching the gas streams to the other exchanger) without interrupting the continuous operation of the system. In addition, since both gas streams are substantially at the same pressure, there are no appreciable pressure shocks to the system when switching from one exchanger to the other. It is a further advantage that a minimum amount of refrigeration is required to purify the incoming air; in fact, only 50 enough refrigeration to create the proper temperature differences between the two gas streams at the cold end of the exchanger, which in actual practice amounts to further cooling the air by about 9° F. In the embodiment shown in Fig. 1, 55 this refrigeration is supplied in the first instance by the liquid air in the liquid air receiver and, as later described, is ultimately furnishing by expanding compressed air with the performance of external work.

The warm pure air entering the liquefaction part of the system through pipe 13 is compressed to a pressure that may vary over a wide range, from as low as 2 atmospheres to more than 200 atmospheres. This compression may be accomplished in one or more stages. In the embodiment

ment shown in the drawings, the air is compressed in two stages in compressors 14 and 15 and the heat of compression is removed after each stage in after-coolers 16 and 17, respectively. The compressors are preferably of the type requiring no internal lubrication to avoid the introduction of impurities into the liquefaction cycle.

The compressed air leaving after-cooler 17 is conducted by a pipe 18 to a heat exchanger 19, where it is cooled by a second portion of cold purified air that is at substantially atmospheric pressure and flowing in a countercurrent direction through the exchanger. Part of the compressed air cooled in exchanger 19 is led by a pipe 20 to an expansion turbine 21, where it is expanded to substantially atmospheric pressure with performance of external work. The refrigeration obtained in the expansion step is sufficient to liquefy the air and to compensate for heat leakage and other thermodynamic losses throughout the system, as well as for the heat absorbed by the liquid air in cooling the incoming air in coil 9. The cold expanded air leaving the turbine 20 is led by a pipe 22 to a pipe 23 that is connected to the liquid air receiver 10 at a point above the level of liquid air therein.

The remainder of the compressed air cooled in exchanger 19 is led by a pipe 24 to a heat exchanger 25, where it is further cooled by indirect heat exchange with the second portion of cold purified air at about its liquefaction temperature flowing in a countercurrent direction. This further cooled air, still under pressure, leaves exchanger 25 by a pipe 26 and, after being throttled by a valve 27 to substantially atmospheric pressure, is discharged as a liquid through pipe 28 into the liquid air receiver 10. As liquid air accumulates in the liquid air receiver, it is withdrawn through valve 30 and discharge pipe 31 into suitable receptacles for transportation to its place of ultimate consumption.

The cold purified air delivered from the expander to pipe 23 is augmented by cold air that is vaporized from the liquid air in the receiver by heat absorbed from warmer air flowing through coil 9 and is also augmented by the vapor flashed from the liquid in pipe 28 on the low pressure side of throttle valve 27. The augmented cold air in pipe 23 passes through exchanger 25 to cool further some of the compressed air and then is led by a pipe 35 through exchanger 19 to cool initially all of the compressed air, as previously described. After leaving exchanger 19, having absorbed as much heat as possible from the compressed air, the warmed pure air is led by a pipe 36 back to compressors 14 and 15, where it augments the supply of warm pure air feed introduced into the liquefaction cycle.

From the foregoing description it will be apparent that only pure air is introduced into the high pressure liquefaction cycle, so that the apparatus in that part of the system will not become plugged with impurities and may be operated continuously for indefinitely long periods. All of the condensable impurities in the entering air are deposited in heat exchangers that form part of the low pressure purification cycle, which may likewise be operated continuously. The refrigeration required in the entire system is obtained from the expansion of air in the liquefaction cycle. The amount of refrigeration produced by the expansion of air in the expander 21 can be controlled by operation of valves 40 and 41 in pipes 20 and 24, respectively, which permit the

passage of more or less air through the expander. If desired, similar valves could be operated automatically in response to the level of liquid air in the receiver 10.

The modifications shown in Figs. 2, 3, and 4 illustrate alternative methods of further cooling the incoming air after it has been purified. As previously indicated, this additional cooling is required to create the proper temperature difference between the two gas streams at the cold end of exchanger 4.

In Fig. 2, the purified air is further cooled after it leaves the accumulator 7 by direct heat exchange with liquid air in the receiver 10 by allowing it to bubble through the liquid as it issues from pipe 8. It is thereby cooled to about its liquefaction temperature and commingles with vaporized air at the top of the receiver. The amount of this commingled cold purified air that is necessary to cool and purify the incoming air is withdrawn through pipe 11 and introduced into the cold end of the heat exchangers, as previously described. The remainder augments the supply of cold air in pipe 23.

In Fig. 3, the further cooling of the incoming purified air after it leaves the accumulator 7 is accomplished by passing it through exchanger 50, where it is cooled indirectly by liquid air from pipe 28 flowing through the same exchanger. Some of this liquid air is thereby vaporized; and this vapor, with the remaining liquid, is then discharged into the receiver 10.

In Fig. 4, this further cooling is accomplished by indirect heat exchange in exchanger 51, in which the cooling agent is the second portion of cold purified air at about its liquefaction temperature in pipe 23, of which there is sufficient supply to accomplish the desired cooling.

According to the provisions of the patent statutes, we have explained the principle of our invention and have illustrated and described what we now consider to represent its best embodiment. However, we desire to have it understood that, within the scope of the appended claims, the invention may be practiced otherwise than as specifically illustrated and described.

We claim:

1. The method of purifying and liquefying a gaseous fluid that includes the following steps: a purification cycle that comprises providing a stream of warm unpurified gaseous fluid at substantially atmospheric pressure, initially cooling this stream by indirect heat exchange to a temperature slightly above its liquefaction temperature to purify it by condensing its low volatile impurities, further cooling the purified stream to obtain purified gaseous fluid at about its liquefaction temperature by heat exchange with cold purified fluid from a subsequent liquefaction cycle, utilizing a first portion of cold purified gaseous fluid to effect the initial cooling of the unpurified stream, and then withdrawing this first portion from the purification cycle; and a liquefaction cycle that comprises compressing at least some of the first portion of purified gaseous fluid withdrawn from the purification cycle, initially cooling the compressed fluid by indirect heat exchange, further cooling one part of the initially cooled compressed fluid by indirect heat exchange to liquefy at least some of it, throttling this part to substantially atmospheric pressure to cool it further, further cooling the remainder of the initially cooled compressed fluid by expanding it to substantially atmospheric pressure with performance of external work to augment the sup-

ply of purified gaseous fluid at about its liquefaction temperature, utilizing a second portion of cold purified gaseous fluid successively to effect said further cooling of the first part of the initially cooled compressed fluid and said initial cooling of all of the compressed fluid, and then compressing and recycling at least some of this second portion of purified gaseous fluid in the liquefaction cycle along with at least some of said first portion of purified gaseous fluid.

2. A method according to claim 1, in which the further cooling of the purified stream is effected by heat exchange with cold purified liquid fluid produced in a subsequent liquefaction cycle.

3. A method according to claim 1, in which the further cooling of the purified stream is effected by direct heat exchange with cold purified liquid fluid produced in a subsequent liquefaction cycle, thereby boiling the liquid fluid, and in which the first portion of cold purified gaseous fluid utilized to effect the initial cooling of the unpurified stream comprises a mixture of the further cooled purified stream and of purified gaseous fluid resulting from said boiling of liquid fluid.

4. A method according to claim 1, in which the further cooling of the purified stream is effected by indirect heat exchange with purified liquid fluid produced in a subsequent liquefaction cycle, and in which the first portion of cold purified gaseous fluid utilized to effect the initial cooling of the unpurified stream is the further cooled purified stream.

5. A method according to claim 1, in which the further cooling of the purified stream is effected by indirect heat exchange with the second portion of purified gaseous fluid at about its liquefaction temperature produced in a subsequent liquefaction cycle, and in which the first portion of cold purified gaseous fluid utilized to effect the initial cooling of the unpurified stream is the further cooled purified stream.

6. A method according to claim 1, in which the gaseous fluid to be purified and liquefied is air.

7. Apparatus for purifying and liquefying a gaseous fluid that includes a purification cycle comprising a purifying heat exchanger for countercurrent flow at substantially atmospheric pressure of a stream of unpurified gaseous fluid and a first portion of a cold purified gaseous fluid to purify the stream by cooling it and condensing therefrom its low volatile impurities, and heat exchange means for further cooling the purified stream to obtain purified gaseous fluid at about its liquefaction temperature by bringing the stream into heat exchange relation with cold purified fluid from a subsequent liquefaction cycle; and a liquefaction cycle comprising a compressor for compressing at least some of said first portion of purified gaseous fluid leaving the purifying heat exchanger, a countercurrent heat exchanger for initially cooling the compressed fluid, a liquefier for receiving one part of the initially cooled compressed fluid and liquefying at least

5 a portion thereof by indirect heat exchange, a throttle valve for reducing the pressure of that part to substantially atmospheric pressure to cool it further, an expander for expanding the remainder of the initially cooled compressed fluid to substantially atmospheric pressure with performance of external work to cool that remainder further to about its liquefaction temperature to augment the supply of purified gaseous fluid at 10 that temperature, conduits for successively conducting a second portion of cold purified gaseous fluid as a cooling agent to the liquefier and then to the countercurrent heat exchanger, and a conduit for conducting said second portion of purified gaseous fluid from the countercurrent heat exchanger to the compressor to augment the supply of compressed purified gaseous fluid.

8. Apparatus according to claim 7, in which said heat exchange means for further cooling the purified stream comprises means for conducting the stream into heat exchange relation with cold purified liquid fluid produced in a subsequent liquefaction cycle.

9. Apparatus according to claim 7, in which 25 said heat exchange means for further cooling the purified stream is indirect, comprising a heat exchanger in which the cooling agent is cold purified liquid fluid produced in a subsequent liquefaction cycle.

10. Apparatus according to claim 7, in which said heat exchange means for further cooling the purified stream is direct, comprising a receiver for holding purified liquid fluid produced in a subsequent liquefaction cycle, said receiver having an opening below the level of liquid therein for admitting the initially cooled purified stream, whereby the stream will bubble through the liquid and be further cooled and at the same time will cause some of the liquid to boil.

11. Apparatus according to claim 7, in which said heat exchange means for further cooling the purified stream is indirect, comprising a heat exchanger in which the cooling agent is a second portion of cold purified gaseous fluid produced in a subsequent liquefaction cycle.

12. Apparatus according to claim 7, in which the gaseous fluid to be purified and liquefied is air.
